UNITED STATES PATENT OFFICE.

LOUIS PLEIN, OF CHICAGO, ILLINOIS.

DESIGN FOR A TEMPERATURE-INDICATING INSTRUMENT FOR MOTOR VEHICLES.

Application filed February 21, 1923. Serial No. 5,233. Term of patent 7 years.

To all whom it may concern:

Be it known that I, LOUIS PLEIN, a citizen of the United States, residing at Chicago, in the county of Cook and State of Illinois, have invented a new, original, and ornamental Design for a Temperature-Indicating Instrument for Motor Vehicles, of which the following is a specification, reference being had to the accompanying drawing, forming part thereof.

Figure 1 and Figure 2 are front and side elevational views, respectively, showing my new design for a temperature indicating instrument for use with automobile radiators or the like.

I claim:—

The ornamental design for a temperature indicating instrument for motor vehicles substantially as shown.

LOUIS PLEIN.
